(57) **CLAIM**

The ornamental design for a refrigerator having air cleaner, as shown and described.

DESCRIPTION

FIG. 1 is a front, left side, perspective view of a refrigerator having air cleaner showing our new design;

FIG. 2 is a front view thereof;

FIG. 3 is a rear view thereof;

FIG. 4 is a left side view thereof; and,

FIG. 5 is a right side view thereof.

The broken lines indicate unclaimed portion of the article that form no part of the claimed design.
